UNITED STATES PATENT OFFICE.

SIDNEY H. HUSTON, OF HOUSTON, TEXAS.

WELL-BORING APPARATUS.

Application filed June 1, 1922. Serial No. 565,130.

To all whom it may concern:

Be it known that I, SIDNEY H. HUSTON, citizen of the United States, residing at Houston, in the county of Harris and State 5 of Texas, have invented certain new and useful Improvements in a Well-Boring Apparatus, of which the following is a specification.

This invention relates to new and useful 10 improvements in a well boring apparatus.

One object of the invention is to provide an apparatus of the character described especially designed for the purpose of assisting 15 in the removal of the pipe that may become stuck in the well bore. In well drilling operations the pipe often becomes stuck in the bore to such an extent that the pipe will be so securely stuck in the 20 bore that it can not be pulled. It is one object of this invention to provide an auxiliary apparatus to be carried by the pipe whereby a fluid course, or fluid courses may be formed through the caved in formation 25 so as to permit a return of the fluid forced down through the pipe and thereby the caved in formation may be gradually washed away so as to release and loosen the pipe to permit the same to be pulled from 30 the bore.

With the above and other objects in view the invention has particular relation to certain novel features of construction, arrangement of parts and use, an example of which 35 is given in this specification and illustrated in the accompanying drawings, wherein:—

Figure 1 is a side view of one form of the device.

Figure 2 is a side view of another form 40 of the device.

Figure 3 is a transverse sectional view thereof taken on the line 3—3 of Figure 2.

Figure 4 is a vertical sectional view of another form of the device and,

Figure 5 is a transverse sectional view 45 thereof taken on the line 5—5 of Figure 4.

In the drawings the numeral 1 designates the pipe in the bore. Suitable wires or cables as 2, 2, Figure 1, are arranged on 50 each side of this pipe and their lower ends are secured to the lower end of the pipe and extend up through the bore to the ground surface. In the form shown in Figure 1 the lower ends of the wires or cables 2 are secured to the pipe by wrapping 55 wire 3 therearound.

In the form shown in Figures 4 and 5 a single wire as 4 is passed through oppositely disposed perforations 5, 5 in the lower end of the pipe and the ends of said wire 60 or cables 4 pass up on each side of the pipe to the ground surface. In case the pipe becomes stuck an upward pull is exerted on the wires or cables 2, or 4, these wires 2 and 4 are made weaker at their lower ends so 65 that they will readily break in case an upward pull is exerted, and the wire 4 is made weak at the point 6 so that it will break in two in case an upward pull is exerted. When these wires or cables are oscillated or 70 moved sideways or withdrawn they will leave open fluid courses up through the caved in formation and fluid may then be forced downwardly through the pipe 1 and it will return through said water 75 courses. As said water is forced under considerable pressure it will soon wear away and enlarge the fluid courses by erosion and the caved in formation will gradually be partly or entirely washed out so as to loosen up 80 the pipe to permit it to be withdrawn.

In Figure 2 I have shown a pair of oppositely disposed housings 7, 7 which are secured to the lower end of the pipe in any preferred manner, preferably by wrapping 85 wire 8 therearound. Within these housings are yieldable members as 9 or 10. The yieldable member 9 has its lower end attached to the lower end of the housing and to its upper end there is attached a wire 90 or cable 11 which extends up alongside the pipe to the ground surface. The yieldable member 10 has its upper end secured to the upper end of the housing and the wire or cable 12 has its lower end attached to 95 the lower end of said yieldable member and it passes up alongside the pipe 1 to the ground surface. In case the pipe becomes stuck in the bore the wires or cables 11 and 12 may be pulled upwardly and released, and when released the members 9 and 10 will pull them back downwardly and this process may be repeated until a fluid course of considerable dimensions is formed 100 through the surrounding material around the pipe and then the wires or cables 11 and 12 may be pulled upwardly until they break near their lower ends, said wires or cables being weakened at the point where they should break. They are then withdrawn and fluid forced under pressure 110 down through the pipe 1 and this water re-

turns through said fluid courses on the outside of the pipe and gradually erodes away the formation so as to loosen up the pipe and permit it to be withdrawn.

5. What I claim is:—

1. In well boring apparatus the combination with a pipe of flexible members on the outside of the pipe one on each side extending from near the bottom of the pipe 10 up to the ground surface, said members being awakened at or near their lower ends.

2. In well boring apparatus the combination with a pipe of a flexible member, on the outside of the pipe said member having 15 a yieldable connection to the pipe near its

lower end and extended up to the ground surface alongside the pipe.

3. In a well boring apparatus the combination with a pipe of flexible members yieldably connected to the pipe near its lower 20 end, said members extending up alongside the pipe on the outside to the ground surface.

In testimony whereof I have signed my name to this specification in the presence 25 of two subscribing witnesses.

SIDNEY H. HUSTON.
